UNITED STATES PATENT OFFICE.

THOMAS A. GILLESPIE, OF WEST ORANGE, NEW JERSEY.

STEAM-BOILER.

SPECIFICATION forming part of Letters Patent No. 729,757, dated June 2, 1903.

Application filed October 22, 1902. Serial No. 128,233. (No model.)

To all whom it may concern:

Be it known that I, THOMAS A. GILLESPIE, a citizen of the United States, residing at West Orange, county of Essex, State of New Jersey, have invented certain new and useful Improvements in Steam-Boilers, of which the following is a specification, reference being had to the drawings accompanying and forming part of the same.

10 My invention relates to steam-generators, and has for its object to produce a boiler which shall avoid certain of the defects commonly found in boilers as heretofore constructed. Steam-generators of the boiler type are usually built up of a large number of small plates riveted together, and considerable difficulty is experienced in making the numerous seams tight and strong enough to withstand heavy pressures, especially in the transverse 15 or circumferential seams, in which the lapped plates must be fitted to each other with great nicety. The exposure of such seams to the high temperature of the furnace presents further disadvantages. The double thickness of 20 metal at each joint not only requires an appreciably longer time for the heat to penetrate to the interior, but the underlap, being thus screened, does not expand as rapidly as the outer one, which is exposed directly to the 25 heat, with the result that both tensile and shearing strains are produced, tending directly to open the seams. My invention, however, obviates these defects, for the reason that longitudinal joints only are employed, 30 transverse or circumferential seams being entirely dispensed with, and for the further reason that none of the seams is directly exposed to the flames. These characteristics are secured by making the shell of two or more 35 plates each the full length of the boiler, a construction which will be more readily understood by referring to the drawings, in which—

Figure 1 is a section of my boiler and a furnace to heat the same. Fig. 2 is a perspective 40 view of the shell without heads. Fig. 3 shows a convenient method of securing the heads to the shell, and Fig. 4 is a section showing a boiler made of three plates.

The shell shown in Figs. 1, 2, and 3 consists 45 of two plates 1, 2, bent transversely to their

longitudinal axes and having their edges upset or thickened, as at 3, 4. These are locked firmly and securely together by means of locking-bars 5, which are bent down around the upset edges. Not only is such a joint cheaper, 55 but extended tests and practical use have shown it to be superior to a riveted seam as to strength and tightness.

The boiler is arranged in any convenient manner over a furnace, for example, as shown 60 in Fig. 1. As will be seen, the lock-bar joints are removed from the direct heat of the firebox, so that both adjacent edges of the upper and lower plates are heated practically at the same time, while on the exposed part of the 65 shell there are no joints or seams of any kind. The stresses and strains common to the old type are thus eliminated, and if under unusual conditions these strains should be produced my boiler is better able to stand them, since 70 the material has not been weakened by numerous rivet-holes. The heads may also be secured to the shell by means of lock-bars, as will be seen in Fig. 3, in which a locking-ring 75 6 engages the upset ends of the plates 1 and 2 and the edge of the flanged head 7.

The size of boiler, which may be made of two plates, is of course limited by the size in which plates can be made; but if it becomes necessary for this reason to use three sheets 80 they may be utilized, as illustrated in Fig. 4. In this case the joints are directly exposed to the fire; but there at most only two such, and the troublesome transverse seams are absent. Furthermore, the edges of the sections are 85 both covered by the same amount of metal in the lock-bar, so that both are heated equally, thus still avoiding the strains before mentioned.

The forms shown I consider convenient; but 90 it will be understood, of course, that my invention is capable of many embodiments, and it is therefore not limited to those described. For example, the boiler may be made of a single plate bent till the edges meet and a 95 single locking-bar to join them. This I consider clearly within the scope of my invention.

What I claim is—

1. A boiler having no transverse seams between the heads having the contiguous plate 100

edges thickened or upset and a longitudinal locking-bar firmly gripping said edges, as and for the purposes set forth.

2. The combination with a furnace, of a longitudinally-jointed boiler having no transverse joints between its heads having its longitudinal joints formed by locking-bars un-

exposed to the direct heat of said furnace, as and for the purposes set forth.

THOMAS A. GILLESPIE.
